United States Patent Office.

THOMAS W. R. RAYNER, OF NEW YORK, N. Y.

Letters Patent No. 95,266, dated September 28, 1869.

IMPROVED WASH-BOILER TUBE.

The Schedule referred to in these Letters Patent and making part of the same.

To all whom it may concern:

Be it known that I, THOMAS W. R. RAYNER, of New York, in the county and State of New York, have invented a new and improved Wash-Boiler Tube.

Figure 1 represents a side elevation of my improved wash-boiler tube, placed in a boiler and in operation.

Figure 2 is a vertical section, taken in the line *xx*, fig. 1.

Similar letters indicate the same parts in both drawings.

This invention relates to an improved tube for a wash-boiler, through which the water circulates, when heated, by rising and pouring out at the top like a fountain, and after falling upon the clothes in the boiler, passes through them and re-enters the tube at the bottom, the operation being continued until the clothes in the wash-boiler are thoroughly cleansed by the repeated passage of the water through them.

My improvement consists in forming a double tube, or enclosing one tube within another, whereby the circulation of the water is rendered more active, and the operation of washing or cleansing the clothes is performed much quicker than with the ordinary single tube.

This has been fully proved by experiment, and is accounted for by the fact that the column of water contained by the inner tube does not part with its heat so quickly while rising.

The water between the inner and outer tubes has a higher temperature than the water outside of the tube among the clothes in the boiler, and, therefore, the heat is not absorbed as rapidly from the column of water in the inner tube as it is from that in a single tube, acted upon directly by the lower temperature of the water outside of the tube, in the usual way. The water, consequently, rises quicker in the inner tube, and discharges at the top at a higher temperature, thus producing greater activity in the circulation of the water, and rendering the operation more effective.

Another improvement in my tube is the attachment, to the top, of a sliding cap or valve, which remains closed, and prevents the escape of steam until the water is hot enough to rise and force the cap up

to discharge itself, and thereby greatly expedite the operation of washing clothes.

My improved wash-boiler tube is made separate and detached from the boiler, in order that it may be applied to and used with any common wash-boiler, instead of the ordinary stationary tube attached to a boiler, having a perforated false bottom; and for this purpose I construct the tube with a broad or bell-mouthed perforated base, which sits upon the bottom of a boiler, and supports the tube in an upright position.

The tube is made of tin or other suitable sheet-metal, with an external shell, A, made slightly tapering, or smaller at the upper than the lower end, in which external tube A is enclosed an internal tube, B, with a small space between them, secured together by small braces *ee*, at top and bottom, as shown in fig. 2.

On the lower end of the tube A is affixed the bell-mouthed base C, perforated by slots *aa*, through which the water can pass for circulation.

On the top of the tube A is attached a sliding cap, D, which closes the upper end when it is down, and opens it when it is raised, by the water forcing itself upward, when boiling, to discharge over among the clothes, passing down through them and through the slots *aa* in the base C, to produce a circulation, which is maintained actively in my improved boiler-tube, by the column of water rising through the inner tube B, with loss of heat, in its passage upward, by conduction, which takes place in a single tube, as before described.

Having described my invention,

What I claim, and desire to secure by Letters Patent, is—

1. A detached wash-boiler tube, having an internal tube, B, combined with an external tube, A, and a base, C, arranged and operating substantially as and for the purpose herein described.

2. The sliding cap D, in combination with the tubes A and B, arranged and operating as herein described.

Witnesses: THOS. W. R. RAYNER.

I. MACDANIEL,

L. J. WATSON.
